UNITED STATES PATENT OFFICE.

JAMES NELSON REYNOLDS, OF JERSEY CITY, NEW JERSEY.

ROD-BENDING MACHINE.

1,274,936.

Specification of Letters Patent. Patented Aug. 6, 1918.

Application filed May 23, 1918. Serial No. 236,154.

To all whom it may concern:

Be it known that I, JAMES NELSON REYNOLDS, a citizen of the United States, and a resident of Jersey City, in the county of 5 Hudson and State of New Jersey, have invented a new and improved Rod-Bending Machine, of which the following is a full, clear, and exact description.

This invention relates to rod bending machines of the type intended particularly for use in bending or shaping the reinforcement rods employed in large concrete building constructions.

Among the objects of the invention is to 15 provide a machine of the character indicated having facilities for insuring rapidity, facility and uniformity in the bending of an unlimited number of such rods. According to the specifications of the building, 20 having reference to the height, thickness or other structural details of a wall or the like, the reinforcement rods are required to be bent or shaped in a predetermined manner, and preferably all of the rods of the 25 same character ought to be bent similarly or with uniformity so that the angles or bends will be equal and the lengths or spans between the bends shall likewise be equal, each to each.

30 A still further object of the invention is to provide a machine whereby a man having no more than ordinary skill may be able to direct the operation of a number of boys or unskilled men, and thereby bend an unusually large number of rods in an accurate manner in a given time.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had 45 to the accompanying drawings, in which like reference characters designate the same parts in the several views, and in which—

Figure 1 is a front elevation of a preferred embodiment of the invention.

50 Fig. 2 is a plan view of the same indicating also a bar held thereon and being bent.

Fig. 3 is a vertical transverse section on the line 3—3 of Fig. 1.

55 Fig. 4 is a detail perspective view of one

of the adjustable tables and showing also an extension member carried thereby; and

Fig. 5 is a perspective view of an implement in the form of an iron gas pipe employed in manipulating the rods. 60

Referring now more specifically to the drawings, I show my machine as comprising a base having front, rear and intermediate longitudinal parallel stringers 10, 11 and 12 respectively, all preferably connected 65 or held in spaced relation to one another by any suitable number of horizontal sleepers 13 shown in this instance as four in number substantially equally spaced with respect to one another. 70

In the construction illustrated I provide two supporting or work holding tables shown at A and B. Each of these tables may be described as comprising a pedestal and a longitudinally adjustable bed. The 75 pedestal of the table A comprises uprights 14 fixed upon the stringers 10 and 12 and a suitable number of diagonal braces 15 leading rearward and downward to the stringer 11. The pedestal also includes a table top 80 16 having parallel upwardly projecting flanges 17 and 18 constituting guides for the bed 19. The guides 17 and 18 are provided with transversely aligned pairs of holes 20 through any pair of which may be passed 85 a bar 21 which likewise passes through the transversely aligned holes 22 formed in the projecting ends of a pair of side rails or ribs 23 constituting the means fixed to the bed for direct coöperation with the guide 90 members 17 and 18 of the table top. Since the bed 19 is adapted to be adjusted longitudinally along the table top and within the overhanging flanges 17 and 18 it is preferable for both ends of the ribs 23 to project beyond the adjacent ends of the main portion of the bed and be provided with 95 holes 22 as best shown in Fig. 4. The bar 21 obviously may be employed at either end of the bed that is most convenient, the purpose of which is to prevent the longitudinal movement of the bed with respect to the 100 table top during the operation of the machine.

The general construction of the table B 105 is similar to that of table A but in addition to its being supported upon the stringers is so arranged as to be adjusted lengthwise thereon. The uprights 14^a rest upon the stringer 10 and are provided with brackets 110

24 that engage down around the front face of said stringer 10 whereby the upward or rearward movement of the table B is prevented with respect to the stringer 10.

5 The uprights 14^b are supported upon the stringer 12 while one or more horizontal pins 25 pass through the lower ends thereof and an upwardly projecting flange 26 having holes 26'. Diagonal braces 15^a extend

10 downward and rearward into co-operation with the back stringer 11 through which one or more pins 27 are projected, thereby locking the rearmost portion of the table B to an upwardly projecting flange 28 constituting a part of the stringer 11 and provided with horizontal holes 28'. While the table A is fixed to the base of the machine, the adjustment provided for the table B will accommodate the machine to all different

15 lengths or weights of reinforcement rods to be bent, subject to certain other adjustments referred to below. The adjustments, however, in the main are accomplished by other means than the adjustment of the table B.

20 25 The bed and table top of table B are practically the same as the corresponding parts described above in connection with table A and hence bear the same reference characters though as a matter of fact they

30 are not interchangeable, one being right handed and the other left, so to speak.

I will now describe the specific design or construction of the several beds 19 having reference especially to Fig. 4. Each bed is

35 provided adjacent to its inner end, or the end directed toward the opposite bed, with an undercut slot 29 along one edge of which are arranged a series of holes 30 equally distant from the slot. The end of the bed

40 opposite the slotted end is provided with a systematically arranged group of vertical holes 31 for the accommodation of one or more, preferably a plurality, of fulcrum pins 32.

45 50 The slot 29 is designed to accommodate a gripping device shown best in Figs. 2 and 3, the same comprising a base portion 33 projecting into and adjustable along the slot, but in practice held in place therein by means of a vertical pin 34 projecting down through the front edge of the base 33 and into one of the holes 30. The gripping device includes also a movable jaw member 35 movable forward and rearward

55 with respect to the jaw portion of the base member 33 but held from displacement by means of two guide studs 36 fixed in the base and projecting through transverse slots 35' in the movable jaw member. The rear

60 edge of the base 33 constitutes an upwardly projecting flange 37 bearing one or more hexagonal headed set screws or bolts 38 which bearing against the rear edge of the movable member 35 serve to force the same

65 forward toward the fixed jaw and whereby

a rod R or the like to be bent may be gripped and held in rigid position while it is being bent.

To the rear portion of the tables are connected a plurality of horizontal rearwardly projecting arms 40 braced with diagonal braces 41 which serve as a shelf for a quantity of rods to be bent in the practice of the invention.

The operation of the machine may be briefly summarized as follows: Given a certain specification of rods to be bent for concrete construction and the supply of rods being supported upon the shelf a man having one or more unskilled helpers may manipulate the machine for the purpose of bending the rods into as many angles as desired and with spans according to the specifications. Each rod in turn will be lifted from the shelf and put upon the two tables, the same being received between the jaws of the respective gripping devices where it will be held until the ends of the rod are suitably bent. The fulcrum pins 32, the number and location of which in the holes 31 will be determined by the specifications aforesaid, will be fixed according to the uniformity desired for the rods. While the rod is put upon the tables in substantially straight condition the operator at either end thereof will slip upon the free end the implement 42, the free end of the rod projecting to any length beyond the implement, and the operator will then apply force to the implement as a lever around the first pin 32 as a fulcrum forming an angle in alignment with the central or main portion of the rod R. He will then slip the tubular lever outward toward or over the end of the rod and apply it as a lever similarly but in the opposite direction bringing the unbent end of the rod around the next fulcrum pin 32 as indicated in Fig. 2. The same operation may be taking place at the opposite end of the rod or the opposite end may be bent at different angles or spans at the same time by another operator with a similar implement 42.

When a relatively long transverse span r is required for the rod I employ an extension such as indicated at 43 in Fig. 4 the same constituting a rigid arm having a shoulder 44 around which the rod may be bent, the arm 43 being temporarily supported by means of pins 45 dropped into any selected holes 31. If desired the otherwise open end of the slot 29 may be closed by means of a rest 46 fixed to the inner end of the bend in any suitable manner and whereon the rod R may be supported adjacent to the gripping device. This rest serves also to prevent accidental loss of the gripping device from the end of the slot 29.

I claim:

1. In a rod bending machine, the combi-

nation of a base, a plurality of tables supported thereon, one of the tables being adjustable along the base with respect to the other, each table comprising uprights, a 5 table top supported upon the uprights and a bed supported upon the table top, a rod holding device comprising relatively fixed and movable jaws carried by each bed, each bed being provided with a group of systematically arranged vertical holes, and a plurality of anchor pins coöperating with selective holes of the said group and around which the adjacent end of the rod may be bent in succession by a lever action.

15 2. In a rod bending machine, the combination of a base, a table supported upon and adjustable endwise along said base for sup-

porting one end of a rod while it is being bent, said table comprising a table top and a bed supported thereon, said bed being 20 provided with a longitudinal dovetailed slot terminating in the inner end of the bed, a gripping device fitted in and adjustable along said slot and comprising relatively fixed and movable jaws, the end of the bed 25 opposite the gripping device being formed with a group of vertical holes, a plurality of fulcrum pins coöperating with selective holes of said group and around which the adjacent end of the rod may be bent in succession by lever action, and means to support the opposite end of the rod while being so bent.

JAMES NELSON REYNOLDS.
